Primary Examiner — Llorellys Martinez(74) *Attorney, Agent, or Firm* — Larson & Larson; Justin P. Miller; Frank Liebenow(57) **CLAIM**

The ornamental design for a self-mating snap, as shown and described.

DESCRIPTION

FIG. 1 is a perspective view of a self-mating snap showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is an exploded perspective view thereof.

The self-mating snap is shown with a symbolic break in its length. The appearance of any portion of the self-mating snap between the break lines forms no part of the claimed design.
